ELECTRIC SWITCH

Elmer E. Johnson, Bronson, Mich., assignor to
 H. A. Douglas Mfg. Co., Bronson, Mich., a corporation of Michigan

Application January 30, 1941, Serial No. 376,635

14 Claims. (Cl. 200—164)

This invention relates generally to electrical switches, and preferably of the reciprocating type used in conjunction with automotive electrical apparatus.

Many improved principles of design and construction have been embodied in the instrument panels of automotive vehicles, and other panel mountings, and certain of these panels are so arranged with respect to other structure adjacent the rear of the panel, and otherwise, that it becomes difficult to find sufficient space for assembling a complete electric switch in the rear of the panel, in which event it is necessary to first mount the switch casing or body adjacent the rear of the panel or support, after which the operating handle is inserted from the front side of the panel through the panel and into operative connection with the switch mechanism.

Accordingly, the primary object of the invention is to provide an electric switch including, among other things, switch mechanism, means for operating the same, and improved means whereby the mechanism and operating means may be easily and quickly connected and disconnected with respect to each other.

Another important object is to provide improved means for predetermining the position of the resilient means employed for maintaining the switch mechanism in a predetermined position, and at the same time a stop for limiting movement of the switch mechanism in one direction.

Another object of the invention is to provide an electric switch consisting of very few parts which are not likely to get out of order, and which may be economically manufactured and assembled on a production basis.

Other objects and advantages of the invention will appear after reading the description herein-after set forth in connection with the drawing annexed hereto.

Figure 1 is a top view of the switch embodying the invention;

Figure 2 is a top view of the switch shown in Figure 1, with the switch back or contact carrier of insulating material removed;

Figure 3 is an enlarged vertical section, taken substantially on line 3—3 of Figure 1 showing certain details of the switch mechanism;

Figure 4 is an enlarged longitudinal sectional view, taken substantially on line 4—4 of Figure 1 showing other details of construction;

Figure 5 is a sectional view corresponding substantially to Figure 4, showing the manner in which the switch mechanism and operating means therefor may be disconnected with respect to each other;

Figure 6 is an enlarged perspective view of the inner extremity of the operating means; and

Figure 7 is an enlarged perspective view of

that part of the guide of the switch mechanism which is adapted to be operatively connected to the inner extremity of the operating means.

In the drawing, numeral 1 generally designates 5 a rectangular box-like casing; 2 a contact carrier of insulating material; 3 a guide member which forms a part of the switch mechanism; 4 bridge means supported on a carrier 5; 6 a spring carried by the guide 3 for supporting the bridge means 4 and associated carrier 5; 7 is operating means in the form of a rod adapted to be detachably connected to the guide 3; 8 is a biasing means, in the form of a spring carried by the rod 7, interposed between the guide 3 and one 10 extremity of the switch casing whereby to predetermine the position of the guide, and the bridge means 4 relative to the contacts carried by the carrier 2; and 9 is a brace member for the spring 8, all of which will be subsequently described in 15 detail.

Considering now the switch casing, same includes a bottom wall 10, end walls 11 and 12, and side walls 13 and 14. As clearly shown in Figure 2, the end extremities of the side walls 13 and 14 are inturned against the exterior surfaces of the end walls 11 and 12 in order to reinforce the latter to some extent, to counteract any strain placed on the end walls of the casing. The side wall 14 of the casing is provided with a pair of upstanding fingers 15 and 16, the side wall 13 with a pair of similar fingers 17 and 18, and the end wall 11 with a finger 19, all of which are adapted to project through suitable apertures or recesses provided therefor in the carrier or switchback 2, and are bent outwardly over and upon the exterior surface of the carrier to firmly secure the carrier in place as evidenced in Figure 1. The end wall 12 of the casing is provided with a more or less centrally located aperture, within which is firmly secured a tubular bearing member 20. This bearing is provided with an inner reduced extremity which seats within the aperture and is overset or flanged against the inner surface of the wall 12. The switch may 25 be secured to an instrument panel or other support in any manner desired, but is preferably mounted by inserting the outer threaded extremity of the bearing 20 through a hole provided therefor in the support with the abutment 30 22 on the bearing in engagement with the rear side of the support and screwing a nut onto the extremity whereby to clamp the support between the abutment and nut.

The planar bottom wall 10 of the switch casing 35 is preferably provided with a more or less centrally located generally rectangular opening 23 extending transverse to the longitudinal axis of the casing as clearly depicted in Figure 7, and provides means through which a suitable tool 40 may be inserted into the chamber of the casing

for lifting or elevating the guide 3 so that the operating rod 7 may be disconnected from the guide and switch, all of which will be described more in detail later.

The contact carrier or switchback 2 is preferably made rectangular in shape and of a size somewhat larger than the casing 1 so that portions of the carrier project laterally outwardly with reference to the upper extremity of the casing. The carrier may be comprised of a plurality of superimposed flat plies or plates of insulating material. The upper ply 24 is made of stock somewhat heavier than that of the lower ply 25 as it carries the terminal posts generally designated 26 and 27.

Any suitable type of terminal posts may be used but the posts 26 and 27 have proven desirable, and provide means whereby plug conductor terminals may be detachably snapped into connection therewith. Each post is secured to the upper ply 24 by a rivet 28 as illustrated in Figure 4 and includes, among other things, an upstanding generally tubular split cylindrical resilient receptacle 29 and an offset base portion 30. The resilient terminal receptacle is preferably protected from damage or injury by a guard member associated therewith, the latter including a tubular part 31 which surrounds the receptacle 29, and an offset base portion 32 superimposed upon the base portion 30 of the receptacle. The headed rivets 28 pass through the base portions 30 and 32 just referred to, and also through holes provided therefor in the ply 24. The head 33 of each rivet is disposed within an aperture provided therefor in the lower and thinner ply 25 of the carrier, and that end of the rivet opposite the head 33 is overset upon the base 32 of each guard member whereby to secure each post to the upper ply 24. The base 32 of each guard may be provided with a tail portion or lug 34 which projects laterally into a hole 35 in the ply 24 in order to prevent any possible rotation or movement of each terminal post relative to the carrier 2. By this arrangement the terminal receptacles 29 are disposed above and in spaced apart relation to the carrier, and the contact heads 33 of the rivets 28 assume a position flush with the bottom surface of the lower ply 25 so that the contacts are presented to be engaged by the raised round contact portions 36 and 37 provided on the bridge means 4.

The bridge means 4 is preferably in the form of a triangular metal plate having rounded contact portions 36 through 38 provided thereon, one adjacent each corner and equally spaced apart as clearly illustrated in Figure 2. The central part of the bridge is preferably provided with three tubular lugs 39 which project in a direction opposite to that of the raised contact portions 36 through 38 into apertures provided therefor in the bridge carrier 5 as shown in Figures 2 and 3. The lugs 39 are preferably equally spaced apart so that they may be fitted into any of the apertures provided in the carrier, in which event two of the raised contact portions on the bridge 4 will at all times be presented for engagement with the rivet contacts 33 mounted on the carrier 2. The lugs 39 are of a length less than the thickness of the carrier 5 so that the lugs can not under any circumstances engage the spring 6 to cause a short circuit.

The bridge carrier 5 is preferably rectangular or square in shape or of a shape to slidably fit within the confines of the guide member 3, and one marginal side of the carrier is preferably

provided with a notch 40 in order to provide clearance for the inner extremity of the rod 7 when the latter is being assembled and disassembled with respect to the guide 3.

5 The guide member 3 is preferably of channel shape including, among other things, a bottom wall 41 and upturned parallel side walls 42 and 43. The bottom wall 41 may be provided with an upstanding protuberance 44. One end of the 10 helical spring 6 is seated about this protuberance, and its other end engages the bridge carrier 5 and presses the contact portions 36 through 38 of the bridge into engagement with the lower ply 25 of insulating material as clearly shown in Figures 3 through 5 whereby to maintain the electric circuit normally open. The bottom wall 41 of the guide is also preferably provided with a pair of depressions 45, one on each side of the longitudinal axis of the switch casing and between the 15 wall 42 and protuberance 44 of the guide. These depressions 45 cause the guide 3 to normally assume a tilted position with that portion of the bottom wall 41 adjacent the wall 43 engaging the bottom wall 10 of the switch casing on a line 20 slightly to the right of the opening 23, as depicted in Figure 4. In other words only the depressions 45 and the right hand end of the guide 3 slidably engage the bottom wall of the switch casing when the switch is operated. The spring 6 functions to normally hold the guide 3 in the tilted position just referred to and the contact portions of the bridge 4 in engagement with the lower ply 25 of the carrier 2. This arrangement provides a 25 well balanced construction and the bridge is held in position substantially parallel to the ply 25 and the pressure exerted by the spring is well distributed with respect to the guide and bridge means.

The manner in which the operating rod 7 is 30 detachably connected or latched to the guide member 3 will now be considered. The bottom wall 41 of the guide 3 near the wall 43 is provided with a longitudinally extending slot 46 and the wall 43 with a vertical slot 47 which is communicatively connected to the slot 46. These 35 slots together form a generally L-shaped opening. More specifically the slot 46 is disposed and arranged transverse with respect to the opening 23 provided in the bottom wall 10 of the switch casing, and the upper marginal edge of the slot 47 is inturned with respect to the 40 guide 3 to provide a finger or latch 48. The slot 47 is adapted to receive the inner extremity of the rod and the slot 46 provides clearance for 45 said extremity when the rod is being assembled and disassembled with respect to the guide.

The inner extremity of the rod may be made 50 as desired, but as herein illustrated, preferably includes, among other things, an extension 49 generally rectangular in cross-section and of a size somewhat less than the cross-sectional size of the remainder of the rod whereby to provide 55 an abutment 50. A generally square shaped notch 51 is provided adjacent the upper extremity of the extension 49. As the result of this 60 notch the extension is provided with an upturned projection 52 arranged substantially at right angles with reference to the longitudinal axis of the rod. The abutment 50 and that wall 65 of the projection 52 opposite the abutment 50 are arranged in spaced apart relation and constitute the side walls of the notch 51, and the bottom wall thereof is indicated by numeral 53. The extreme end of the integral extension 49 is 70 preferably provided with a cam surface 54 ar-

ranged at an acute angle with reference to the axis of the rod. In short, the rod is provided with a generally L-shaped extension having a cam surface thereon.

The brace member 9, above referred to, at the beginning of this description, is arranged within the casing 1 and rests upon its bottom wall 10 as clearly shown in Figure 2. This brace is preferably constructed from a single piece of flat sheet metal stock, and includes a pair of substantially parallel portions 55, end portion 56 connecting portions 55, and portions 57 which extend outwardly substantially at right angles with reference to the portions 55; and the free extremities of the outwardly extending portions are adapted to more or less frictionally engage the side walls 14 and 15 of the switch casing. One extremity of the spring 8, above referred to, and which is carried by the rod 7, is disposed in that space or pocket formed by the parallel portions 55 of the brace, with one end engaging the end portion 56, and its opposite extremity engaging the upturned wall portion 43 of the guide 3, in order to normally press the opposite upturned wall portion 42 of the guide into engagement with the end wall 11 of the switch casing. Thus, the guide and brace are urged in opposite directions by the spring 8, with the portion 56 of the brace engaging the inner flanged over extremity of the tubular bearing member 20 which receives the rod. The portion 46 is preferably provided with an aperture through which the rod 7 extends. By this improved arrangement, the respective positions of the brace member 9 and the guide 3 are predetermined. More specifically, the aperture in the brace, the axis of the spring 8 and the slot 47 in the guide are arranged in alignment so that the same will properly receive the rod when it is being operatively connected to the guide. The outwardly extending portions 57 of the brace 9 provide abutments which form a stop whereby to limit the outward movement of the guide.

To connect the rod to the guide member 3 forming a part of the switch mechanism, the rod is merely inserted through the bushing 20 from the front side of the instrument panel mounting through the aperture in the brace, through the spring 8, and as the inclined cam surface 54 on the extension 49 of the rod enters the slot 47 and gradually engages the inturned finger or catch 48 on the guide, the lower end of the guide is gradually lifted or elevated until the projection 52 on the extension passes beyond said finger or catch, whereupon, the pressure exerted by the spring 6 carried by the guide causes the raised end of the guide to snap downwardly to engage the bottom wall 10 of the casing, and the catch 48 into the notch 51 between the side walls defining said notch, as clearly illustrated in Figure 4. In view of the fact that the extension 49 is generally rectangular in cross-section, it should be clearly evident that rotation of the rod with respect to the guide is prevented and, of course, this feature is desirable in those instances where an operating knob adapted to be secured to the outer free end of the operating rod is provided with certain indicia which indicia may be quickly and intelligently read only when the indicia is right side up.

To disconnect or release the rod from the guide, it is only necessary to insert a tool, such as that indicated in Figure 5, upwardly into the opening 23 provided in the bottom wall of the switch casing and raise or elevate the lower end

of the guide until the catch 48 on the guide clears the notch 51 on the extension of the rod, whereupon the rod may be freely pulled outwardly entirely apart from the switch. The rod 5 may be again assembled with the switch mechanism by following the procedure set forth in the preceding paragraph.

In view of the foregoing, it is evident that means have been provided whereby operating 10 means for a switch may be easily and quickly assembled or disassembled with respect to the switch mechanism; resilient means whereby to predetermine the position of the switch mechanism; and improved means for predetermining 15 the position of the resilient means with respect to the switch mechanism and other related parts.

Having thus described my invention, it is obvious that various modifications may be made 20 in the same without departing from the spirit of the invention; and, therefore, I do not wish to be understood as limiting myself to the exact form, construction, and arrangement, and combination of parts herein shown and described.

I claim:

1. An electric switch including, a casing, a carrier carrying contacts secured to said casing, switch mechanism having a bridge adapted to cooperate with said contacts, resilient means for predetermining the position of said mechanism, and receiving means disposed entirely within the 30 confines of said casing apart from said mechanism receiving and predetermining the position of a portion of said resilient means with respect to a part of said mechanism.

2. An electric switch including, a casing, a carrier carrying contacts secured to said casing, a guide movable within said casing, a carrier carrying bridge means resiliently mounted in said 40 guide, a resilient element acting on said guide for maintaining same in a predetermined position, means arranged in said casing apart from said guide, said means having a part providing a stop for limiting the movement of said guide in one direction, and a part for receiving said resilient element for maintaining said means in a predetermined position with respect to said guide.

3. An electric switch including, a casing, a carrier carrying contacts supported on said casing, 50 switch mechanism carrying bridge means for said contacts, said mechanism including a wall provided with an aperture, generally tubular resilient means and a brace arranged within said casing, said brace being acted upon by said resilient means to position the axis of said resilient means in alignment with the aperture in said wall.

4. An electric switch including, a casing, an aperture in a wall of said casing, a carrier carrying contacts supported on said casing, switch mechanism carrying bridge means for said contacts, said mechanism including a movable member provided with an aperture, generally tubular resilient means disposed in said casing, and 60 means for locating the longitudinal axis of said resilient means in alignment with both of said apertures.

5. A switch as set forth in claim 4, in which an aperture is provided in said locating means, 70 and said resilient means is similarly located with respect thereto.

6. An electric switch including, a casing, a wall of said casing having an aperture therein, a carrier carrying contacts supported on said casing, movable means supporting bridge means for said 75

contacts, resilient means for maintaining said movable means in a predetermined position, and means loosely arranged within the casing apart from said movable means for maintaining said resilient means in a definite position with respect to said aperture, said resilient means also acting to maintain said loosely arranged means in spaced apart relation to said movable means.

7. A stop member adapted for disposition within the confines of a switch casing for limiting movement of switch mechanism in one direction, said member being comprised of a channel portion adapted to receive means for maintaining the mechanism in a predetermined position, and said channel portion being provided with wings projecting laterally with reference to the longitudinal axis of the channel portion, said wing portions being constructed and arranged to engage the casing to predetermine the position of one extremity of the stop member and at the same time provide abutments which are adapted to be engaged by the switch mechanism for limiting movement of same in a predetermined direction.

8. An electric switch including, a switch casing, a carrier of insulating material carrying contacts mounted on said casing, a guide member supporting contact means adapted to engage the contacts on said carrier, a tubular bearing member carried by a wall of said casing, an actuating rod reciprocably mounted in said bearing and having connection with said guide, and means loosely arranged in the casing disposed between the bearing and the guide in spaced relation with respect to the guide whereby to provide a stop limiting movement of said guide in at least one direction.

9. An electric switch including, a switch casing, a carrier supporting contacts mounted on said casing, switching mechanism carrying contact means adapted for connection with said contacts on said carrier, an actuating rod extending into said casing and connected to said switching mechanism for operating said mechanism, and separate means arranged within said casing in spaced apart relation to said switching mechanism assisting to predetermine the position of the inner extremity of the rod with respect to said mechanism.

10. An electric switch including, a switch casing, a carrier supporting contacts mounted on said casing, switch mechanism carrying contact means adapted for connection with said contacts on said carrier, a tubular bearing member secured to a wall of the casing, an actuating member reciprocably mounted in said bearing and connected to said mechanism for operating same, separate means arranged in said casing between said mechanism and said bearing, and resilient means interposed between said mechanism and said separate means for normally maintaining the latter and said mechanism in spaced apart relation.

11. An electric switch including, a cup-shaped casing having a bottom wall, side walls and end walls, a carrier carrying contacts carried by said casing, a guide member movably arranged in said casing, said guide having a bottom wall and an upstanding wall, an opening in said upstanding wall, bridge means supported on said bottom wall adapted to cooperate with said contacts, means integral with the bottom wall of said guide engaging the bottom wall of said casing for normally maintaining said guide in a tilted position, an aperture provided in one of the end walls of said casing, an actuating rod projecting through

said aperture, the upstanding wall of said guide and the inner extremity of said rod being so constructed and arranged that they may be connected together in latched relation by merely camming the rod into the opening provided in said upstanding wall, and a recess provided in the bottom wall of said casing through which a tool may be inserted for elevating the lower tilted extremity of the guide whereby the rod may be disconnected from the guide.

12. An electric switch including, a cup-shaped casing having a bottom wall, side walls and end walls, a carrier carrying contacts carried by said casing, a guide member movably arranged in said casing, said guide having a bottom wall and an upstanding wall, an opening in said upstanding wall, bridge means supported on said bottom wall adapted to cooperate with said contacts, means integral with the bottom wall of said guide engaging the bottom wall of said casing for normally maintaining said guide in a tilted position, an aperture provided in one of the end walls of said casing, an actuating rod projecting through said aperture, the upstanding wall of said guide and the inner extremity of said rod being so constructed and arranged that they may be connected together in latched relation by merely camming the rod into the opening provided in said upstanding wall, a recess provided in the bottom wall of said casing through which a tool may be inserted for elevating the lower tilted extremity of the guide whereby the rod may be disconnected from the guide, stop means loosely arranged in said casing, and resilient means urging said guide in one direction and said stop means in another direction so that said stop is held in spaced apart relation to said guide.

13. An electric switch including, a switch casing, a carrier carrying contacts carried by said casing, switch mechanism carrying contact means adapted for connection with said contacts on said carrier, an opening provided in a wall of said casing, an actuating member reciprocably mounted in said opening and connected to said mechanism for operating the same, stop means loosely arranged in said casing between said mechanism and said casing wall, resilient means interposed between said mechanism and said stop means for normally maintaining said stop means and said mechanism in spaced apart relation, a recess provided in the bottom wall of said casing opposite the connection between said actuating member and said mechanism whereby a tool may be inserted into the recess to move said mechanism in a direction whereby said actuating member may be disconnected from said mechanism.

14. In an electric switch, a casing, a carrier carrying contacts carried by said casing, switch mechanism arranged in said casing, contact means carried by said switch mechanism adapted to cooperate with the contacts on said carrier, means integral with and projecting from said mechanism engaging the bottom wall of said casing whereby to normally maintain said mechanism in a tilted position, actuating means extending into said switch casing connected to said switch mechanism, and a recess provided in the bottom wall of said switch casing providing means through which a tool may be inserted to elevate the lower end of said switch mechanism to a position whereby said actuating means may be disconnected from said switch mechanism.
